UNITED STATES PATENT OFFICE.

WILLIAM LYON, OF SHEFFIELD, COUNTY OF YORK, ENGLAND.

FLUID-PRESSURE GOVERNOR.

SPECIFICATION forming part of Letters Patent No. 292,241, dated January 22, 1884.

Application filed September 15, 1883. (No model.) Patented in England March 27, 1882, No. 1,472.

To all whom it may concern:

Be it known that I, WILLIAM LYON, a subject of the Queen of Great Britain, residing at Sheffield, in the county of York, England, have 5 invented a new and useful Improvement in Fluid-Pressure Governors, (for which I have obtained British Letters Patent No. 1,472 of 1882, dated March 27, 1882,) of which the following is a specification.

10 My invention relates to improved means for regulating the pressure and flow of gas automatically, and is applicable to either station, district, or consumers' governors, so that, for example, although the pressure in the main or 15 service pipes may be at a high figure and very variable, the pressure in the consumers' pipes may be kept at an unvarying and low pressure. The inlet-pressure may vary from thirty-tenths to fifty-tenths. The outlet may be kept 20 at an undeviating pressure of eight-tenths, (of an inch.)

I am aware that many forms of gas-governors have been designed for the above-described purpose. In such governors heretofore, the 25 pressure of the "inlet-gas" has most commonly been relied on to open or close the inlet-valve, (more or less,) as may be required, to regulate the flow of gas past said valve. The application, instead of the pressure, of the 30 "outlet-gas" has been proposed, and my governor operates on this better principle, whereby the pressure of the outlet-gas may be directly regulated with great nicety, as aforesaid.

The present invention consists in an improved combination and arrangement of parts, 35 in a gas-governor, of great simplicity, utilizing a large pressure-area, adapted to be readily inspected and kept in order, and operating automatically by the pressure of the gas in the 40 outlet or consumer's side of the governor, acting on the surface of a liquid contained in a chamber closed at top, and thus raising or lowering the liquid in an open chamber, which communicates with the former below the surface of the liquid, and contains a float which 45 is connected directly to the inlet-valve. The liquid used may be water, oil, glycerine, or other suitable liquid or mixture.

Two plans or methods of construction of gas- 50 governors according to my invention are illustrated on a sheet of drawings, which accompanies this specification as part thereof.

Figure 1 of these drawings represents a sectional elevation and top view of a governor having two chambers placed side by side; and Fig. 2 represents like views of a preferred form having the float-chamber surrounded by an annular chamber, the latter being a very convenient arrangement.

The same letters of reference indicate corresponding parts in both figures.

My governor in either form is constructed with two compartments or chambers, A, B, A being the float-chamber, and B the closed chamber. The latter communicates with the gas in 65 the outlet or consumer's pipe C by means of the small pipe D. The two chambers A and B communicate under the division-wall E, and are provided with a sufficient quantity of liquid to support the float F at a proper height. 70 This float is connected with the valve G by means of the valve-rod H, which may be secured at the top of the float, either by lock-nuts, as in Fig. 1, or by a ball-nut, as in Fig. 2, or by other equivalent means. The valve-rod 75 passes through a vertical tube, I, which rises from the bottom of the chamber A sufficiently above the surface of the liquid, and which is sealed by an outer tube, J, projecting downward within the float, its top being closed, 80 and its lower end immersed in the liquid. The valve is adjusted to pass the required quantity of gas by means of weights placed on the top of the float, and the latter is suitably constructed and guided in customary manner. It 85 will thus be obvious that the gas will enter the chamber B through the vertical pipe D, and will press upon the surface of the liquid in said chamber B, raising the liquid in the chamber A, and with it the float and valve, until 90 the diminished flow of gas reduces the pressure to the adjusted amount. If, on the contrary, the pressure in the chamber B is reduced by the withdrawal of gas, the valve immediately opens and admits sufficient gas to regain 95 the normal and regulated pressure. In either case the action is instantaneous, the governor being sensitive to the least variation of pressure.

The filling-pipe K and overflow-pipe L (represented in Fig. 1) may be dispensed with and a simple plug, M, Fig. 2, be used instead, the liquid being in this case introduced through the open chamber A.

I do not bind myself to the use of the exact valve shown in the drawings, but I find it in practice simple and effective.

I do not claim, broadly, the combination, in a gas-governor, of an open float-chamber and a closed pressure-chamber communicating with each other near the bottom, and provided with a suitable fluid for transmitting motion through a float to a valve, as I am aware that such a combination exists, of an earlier date, in an "apparatus for regulating the exhauster in gas-works," said closed chamber being connected with the suction-pipe, and said float with the throttle-valve of the fan-driving engine. I am also aware that closed float-chambers, in which the pressure of outlet-gas is utilized for pressure-regulating purposes, have been combined with surrounding fluid-chambers. This I also disclaim.

What I claim as of my invention, and desire to secure by Letters Patent, is—

The combination, in a governor for regulating the pressure and flow of gas, of a chamber closed at top and supplied with a suitable liquid, a communication between this chamber and the gas-outlet or consumer's pipe by which the pressure of the gas in the latter is brought to bear on a large area of liquid surface within this chamber, a second chamber open at top, communicating with the first below the lowest level of the liquid, and a float in said second chamber connected with the gas-inlet valve, substantially as hereinbefore described, for the purposes set forth.

In testimony that I claim the foregoing as my own I have affixed hereto my signature in presence of two witnesses.

WILLIAM LYON.
